UNITED STATES PATENT OFFICE.

MICHAEL J. POWER, OF NEKOOSA, WISCONSIN.

BARK PRESS.

Application filed July 6, 1925. Serial No. 41,508.

This invention relates to bark presses.

The compressing machine disclosed herein has for its object the pressing of bark for the removal of fluids therefrom and for the shaping of such compressed bark into units of convenient sizes that they may be readily handled and burned in furnaces.

In bark pressing machines having foraminous cylinders it has been found that a considerable quantity of fluid remains in the bark adjacent the head of the piston within the cylinder and it is therefore the principal object of this invention to provide a hollow piston adapted to receive the fluids in bark adjacent the head of such piston and also sluicing means communicating with the hollow of the piston for removing such solid particles of the bark as may pass with the fluids to the interior of the piston.

Another defect found in bark pressing machines having a cylinder open at one end and a piston reciprocable in the cylinder is in the difficulty with which the bark pressing operations have been started. In other words, the bark when initially starting the operation tends to freely pass out through the open end of the cylinder without building up a resistance to the movement of the piston and thus drive the fluids from the bark. It has been found also that at times during the bark pressing operations the usual mechanism provided for resisting the emission of the bark from the cylinder fails when the quantity of bark passing through the open end of the cylinder decreases to such an extent as to eliminate that resistance which the cylinder itself offers when it is packed with bark to capacity.

It is therefore a still further object of this invention to provide in bark pressing machines a pivoted resistor jaw automatically adapted to oppose to the passage of bark and to offer a resistance variable inversely with variations occurring in the resistance of the cylinder when the machine is operating at less than full capacity.

In the drawings:

Fig. 1 is a fragmentary plan view of a bark compressing machine.

Fig. 2 is a fragmentary side elevation partly in section of the machine shown in Fig. 1.

Fig. 3 is a section taken on the line 3—3 of Fig. 2.

Fig. 4 is a section taken on the line 4—4 of Fig. 3.

Fig. 5 is a section taken substantially on the line 5—5 of Fig. 2.

Fig. 6 is a fragmentary plan view in section of the rear portion of the cylinder.

Like parts are identified by the same reference characters throughout the several views.

The present application is a companion to my pending application Serial No. 564,626, filed May 29, 1922.

In the embodiment of the invention disclosed herein, the bark compressing machine includes a base 1 having feet 2 for securing such base to a foundation. On the base 1 is secured a cylinder 3 having foraminous side walls 4 and foraminous top and bottom walls 5 and 6, the top wall 5 being provided with an opening 7 for the admission of bark to the cylinder 3. The cylinder is open at 8 for the emission of bark therefrom and is provided adjacent such opening with adjustable members 9 in the side walls 4 for resisting the emission of the bark from the cylinder 3. The members 9 are not shown or described in detail as they form no part of this invention and are fully disclosed in my pending application Serial No. 564,626. The walls 4, 5 and 6 are secured together by tie bolts 10.

Reciprocable within the cylinder 3 is a piston 15 having a detachable foraminous head plate 16 and which is secured to the cross head 17 by rod 18, the cross head being reciprocable in the guide members 19. The cross head in turn is connected by crank rod 20 to reciprocating mechanism (not shown) but which may be such as is disclosed in the above mentioned application, Serial No. 564,626.

The piston 15 is recessed and has a plurality of vertically extending partitions 21 and 22 dividing the recess into chambers 23, 24 and 25 each having a bottom provided with apertures 26 adjacent the sides thereof and central apertures 27. Partitions 21 and 22 act as brace members adapted to absorb pressures upon the intermediate portion of plate 16 caused by bark compressed within the cylinder. The apertures 26 communicate with a rearwardly extending slot or slots 28 in the bottom of the piston. These slots are closed at their front and rear ends and

at all times during the stroke of the piston 16 communicate with drain apertures 29 in the bottom 6 of the cylinder. The drain apertures 29 are connected by the channel 30 secured to the bottom 6 and communicating with the drain pipe 31.

Extending into each of the apertures 34 in the bottom 6 is a water spraying nozzle 35 each positioned for communication with 10 an aperture 27 when the piston is in its retracted position relative to the cylinder. The nozzles 35 are each connected to a common source of water supply by pipe 36 and are at all times during the reciprocation of 15 piston 15 covered by such piston so that water coming from the nozzles will not be sprayed upon bark in the cylinder 3.

At the open end of the cylinder 3 is provided a channel 45 for guiding the bark as it 20 leaves the cylinder. This channel is provided with a bottom 46 substantially in alignment with the bottom 6 in the cylinder and also with sides 47 substantially in alignment with the sides 4 of the cylinder. 25 This channel 45 is secured to the compressing machine by angularly disposed bolts 48 anchored at the sides of the base 1 and bolts 49 passing through the upper flanges of base 1.

30 Supported from and secured to the bottom 46 is a pair of vertically extending rods 50 each disposed adjacent one of the walls 47 and connected at their upper ends by a pivot rod 51. Integral with the top wall 5 of the cylinder is a pair of spaced upstanding lugs 52 and connected at their upper ends by a rod 53. For securing the rods 50 in their vertically upright position, a pair of links 54 are provided each connected with the pivot rod 51 and rod 53 adjacent the ends thereof.

45 Pivots mounted upon rod 51 is a resistor jaw 60 normally extending from rod 51 in a downwardly inclined position toward the open end of the cylinder 3 and provided with side walls 61 and bottom 62 curved upwardly at the free end 63 of the jaw. Supported from the top margins of walls 61 of resistor jaw 60 is a transverse cross support 76 bolted to such walls. Mounted on said support 76 and integral therewith is a pair of spaced standards 64 connected by a pin 65 having a roller 66. Pivoted to rod 53 is an arm 67 having its pivoted end spaced from lugs 52 by bushings 68 upon the rod 53. This arm rests upon the roller 66 disposed between the standard 64 upon the resistor jaw and is provided at its free end with a weight 69 slidably thereon and having a set screw 70 for retaining the weight in any desired position upon the arm 67. For limiting the extent of movement of the resistor jaw 60 into the channel 45 adjustable bolts 75 are threaded to portions of the cross supports 76 projecting laterally upon each side

of the jaw 60 and are each adapted to contact with the walls 47 of the channel 45, thus the extent to which the resistor member or jaw 60 may move into the channel 45 may be determined by the setting of bolts 75.

In operation the device operates as follows: When the piston 15 is in its retracted position as shown in Fig. 2 the bark is fed through the aperture 7 into the cylinder. The piston, then in its forward movement, 75 forces the bark toward the open end 8 of the cylinder and the bark comes into contact with the resistance members 9 and the resistor jaw 60, which members and jaw tend to hold the bark within the cylinder. If the pressure on such bark is not sufficient to drive it past the resistor member or jaw when the piston has completed its forward stroke, such piston will return to its retracted position and additional bark be fed into the cylinder at which time the piston carries the additional bark forward into contact with the bark remaining in the cylinder and creates a pressure sufficient to force some of the bark through the opening 8 in the cylinder. When a predetermined pressure on the bark has been attained the resistor jaw 60 will be moved upwardly about its pivot out of the direct path of the pressed bark to relieve such bark from any excess pressure.

50 The pressure created upon the bark by the piston and resistance members 9 and resistor jaw 60 will force fluids in such bark to pass through the foraminous walls of the cylinder and through the foraminous head of the piston. The fluids passing from the bark through the foraminous plate 16 upon the piston 15 will collect in the recesses 23, 24 and 25 in the piston head, some of the fluid passing through the bottoms of the several recesses and into the slots 28 in the bottom of the pistons.

55 As soon as the piston has completed its forward stroke it will then be moved to its retracted position wherein the apertures 27 in the bottom of the recesses of the piston register with their respective water spraying nozzles 35 to permit water to be sprayed from the nozzles into the recesses. This sprayed water will carry any of the solid matter that may have collected within the recesses by reason of the pressing operation, outwardly through the slots 28, drain aperture 29, channel 30 and drain pipe 31, thus keeping the recesses clean and free from any solid matter.

60 It is apparent that any resistance which the resistor jaw offers to the emission of bark from the cylinder will be transmitted to the upper ends of the rods 50 through the pivot pin 51. To strengthen these rods 50 and to maintain the pivot of the resistor jaw in position, the links 54 are provided secured to the upstanding lugs 52 on the cylinder.

The resistance that the resistor jaw may offer to the emission of bark from the cylinder may be controlled and predetermined by the proper adjustment of the weight 69 upon the arm 67 which acts upon the standard 64 to force the resistor jaw into the channel 45.

The resistor jaw is curved upwardly at its free end 63 to provide a surface upon which the bark may act to force the jaw upwardly when the resistance to the egress of the bark is of sufficient amount to force the fluids from the bark.

While I have provided an adjustable weight for varying the resistance that the resistor jaw may offer to emitted bark, I have also provided adjustable bolts for limiting the extent to which the resistor jaw may extend into channel 45 thereby to determine also the initial resistance that the resistor may offer to the egress of bark from the cylinder 3 at the beginning of the bark pressing operation.

The cylinder and piston operating mechanism (not shown) are secured in relative position by the longitudinally extending tie rods 80 which engage the apertured plate 81 at the open end of the cylinder 3. This arrangement is similar to the arrangement disclosed in my pending application Serial No. 564,626, and is not a part of this invention.

I claim:

1. In a machine for compressing fluid carrying materials, the combination with a cylinder, of a piston reciprocable in said cylinder and having a recessed head, a foraminous plate covering said recess, a drain extending rearwardly along said piston and communicating with said recess, said cylinder being provided with a port adapted to receive fluid from said drain, and sluicing means for washing said recess when said piston is in its extreme retracted position.

2. In a machine for compressing fluid carrying materials, the combination with a cylinder, of a piston reciprocable in said cylinder and having a recessed head, a foraminous plate covering said recess, a drain extending rearwardly along said piston and communicating with said recess, said cylinder being provided with a port adapted to receive fluid from said drain, and sluicing means for washing said recess, said sluicing means being at all times covered by said piston and in communication with said recess only when said piston is in its extreme retracted position.

3. In a machine for compressing fluid carrying materials, the combination with a cylinder, of a piston reciprocable in said cylinder and having a recessed head and longitudinal slot in its bottom communicating with said recess, a foraminous plate covering said recess, a drain pipe communicating

with the interior of said cylinder and adapted to receive fluids from said slot, and a water spraying nozzle extending through the cylinder walls, said recess being open at one side to receive water from said nozzle 70 only when said piston is in its extreme retracted position.

4. In a machine for compressing fluid carrying materials, the combination with a cylinder, of a piston reciprocable in said cylinder and having a recessed head, a foraminous plate covering said recess, a water nozzle extending through the cylinder walls, said recess being open in one side to receive water from said nozzle only when said piston is in its extreme retracted position, and means for draining from said recess fluids therein.

5. In a machine for compressing fluid carrying materials, the combination with a cylinder, of a piston reciprocable in said cylinder and having a plurality of vertically extending recesses and also a plurality of slots in the bottom of said piston extending longitudinally thereof and each communicating with one of said recesses, a drain pipe communicating with each of said slots and a plurality of water spraying nozzles in the bottom of said cylinder, each of said recesses having their bottoms open to receive water from a corresponding nozzle only when said piston is in its extreme retracted position.

6. In a machine for compressing fluid carrying materials, the combination with a cylinder having a plurality of drainage openings in its lower side, of a piston reciprocable in said cylinder and having a plurality of vertically extending recesses covered by a foraminous head plate, said piston being provided with a plurality of longitudinally extending slots each communicating with a recess and registering throughout its length with one of said drainage openings during the reciprocation of said piston, and a plurality of water spraying nozzles extending through one side of said cylinder for registry with corresponding recesses in the extreme retracted position of said piston, said piston when moved from its extreme retracted position substantially covering said nozzles.

7. In a machine for compressing fluid carrying materials, the combination with a cylinder having a plurality of drainage openings, of a piston reciprocable in said cylinder and having a plurality of recesses extending transversely thereof and covered by a foraminous head plate, said piston being provided with a plurality of longitudinally extending slots each communicating with a recess and registering throughout its length with one of said drainage openings during reciprocation of said piston, and a plurality of water spraying nozzles extend-

ing through one side of said cylinder for registering with corresponding recesses in the extreme retracted position of said piston, said piston when moved from its extreme 5 retracted position substantially closing said nozzles.

8. In a machine for compressing fluid carrying materials, the combination with a cylinder having a plurality of drainage 10 openings in its lower side, of a piston reciprocable in said cylinder and having a plurality of vertically extending recesses covered by a foraminous head plate, said piston being provided with a plurality of 15 longitudinally extending slots each communicating with a recess and registering throughout its length with one of said drainage openings during reciprocation of said piston, and a plurality of water spraying 20 nozzles in the lower side of said cylinder for registry with corresponding recesses in the extreme retracted position of said piston, said piston when moved from its extreme 25 retracted position substantially closing said nozzles.

9. In a machine for compressing fluid carrying materials and including a cylinder open at one end and a piston reciprocable in said cylinder, a resistor jaw pivotally supported adjacent the open end of said cylinder and normally extending downwardly at an angle from said pivot toward the open end of said cylinder.

10. In a machine for compressing fluid carrying materials and including a cylinder open at one end and a piston reciprocable in said cylinder, a resistor jaw pivotally supported adjacent the open end of said cylinder and inclined downwardly from said pivot toward said cylinder, said jaw having its free end adjacent said cylinder provided with an upwardly curved bottom.

11. In a machine for compressing fluid carrying materials and including a cylinder open at one end and a piston reciprocable in said cylinder, a pivotally supported resistor jaw normally inclined downwardly from said pivot toward the open end of said cylinder and having its free end extending

upwardly from the bottom of said resistor 50 jaw, and adjustable means for varying the resistance of said jaw to the egress of material from said cylinder.

12. In a machine for compressing fluid carrying materials and including a cylinder 55 open at one end, a channel open at its top and comprising an extension of said open end, a resistor member pivotally supported remote from said end and adapted to extend downwardly into said channel at an angle 60 extending from said pivot toward said open end.

13. In a machine for compressing fluid carrying materials and including a cylinder open at one end, a channel open at its top 65 and comprising an extension of said open end, a resistor member pivotally supported remote from said end and adapted to extend downwardly into said channel at an angle 70 extending from said pivot toward said open end, and means co-acting with the sides of said channel for limiting the downward movement of said member.

14. In a machine for compressing fluid carrying materials and including a cylinder 75 open at one end, a channel open at its top and comprising an extension of said open end, a resistor member pivotally supported remote from said end and adapted to extend downwardly into said channel at an angle 80 extending from said pivot toward said open end, and adjustable means co-acting with the sides of said channel for limiting the downward movement of said member.

15. In a machine for compressing fluid carrying materials and including a cylinder open at one end, a channel open at its top 85 and comprising an extension of said open end, a resistor member pivotally supported remote from said end and adapted to extend 90 downwardly into said channel at an angle extending from said pivot toward said open end, a means adjustably carried by said member and adapted to contact with the upper margin of the sides of said channel, whereby the extent of downward movement of said member may be predetermined.

MICHAEL J. POWER.
